UNITED STATES PATENT OFFICE.

JOHN MCFARLANE AND EDWARD D. STERNE, OF WASHINGTON, DISTRICT OF COLUMBIA, ASSIGNORS OF ONE-HALF TO OBADIAH A. PURDEY, OF WASHINGTON, DISTRICT OF COLUMBIA.

INCANDESCENT BURNER FOR OIL-LAMPS.

SPECIFICATION forming part of Letters Patent No. 690,117, dated December 31, 1901.

Application filed March 30, 1901. Serial No. 53,671. (No model.)

To all whom it may concern:

Be it known that we, JOHN MCFARLANE and EDWARD D. STERNE, citizens of the United States, residing at Washington, in the District of Columbia, have invented new and useful Improvements in Incandescent Burners for Oil-Lamps, of which the following is a specification.

Our invention relates to improvements in incandescent burners for oil-lamps; and it consists in the novel features of construction hereinafter described, reference being had to the accompanying drawings, which illustrate one form in which we have contemplated embodying our invention; and said invention is fully disclosed in the following description and claims.

Referring to the drawings, Figure 1 is a vertical sectional view of our device. Fig. 2 is a vertical section of a modification. Fig. 3 is a vertical sectional view of still another modification, and Fig. 4 is a perspective view of the air-inlet-valve disk.

The object of our invention is to provide an improved incandescent burner for use in connection with oil-lamps whereby the gas generated about the wick is thoroughly mixed with air, combustion thereby rendered more complete, and a better flame afforded with which to heat the mantle.

A reservoir A, having an internal air-inlet tube B, is provided with the chimney-support C, secured in a suitable opening in the top of the same. This support C is cylindrical in form, is provided with perforations c' near the upper portion, as at c, and with a flange c². This flange c² has perforations c³, a mantle-support c⁴, and chimney-retaining prongs c⁵. A suitable opening c⁶ in the support C and a door c⁷ (shown in Fig. 1) are adapted to be used as a means of access in lighting. A wick D surrounds the air-inlet tube B and operates within the cylindrical support C. The usual arm E, having a thumb-piece e and provided with the wick-clip (shown in dotted lines) is arranged to project through the top of the reservoir for operating the said wick D.

Within the air-inlet tube B is an air-con-

trolling inlet-valve, which consists of the tube 50 F, having an angular flange f and a fluted disk G, hereinafter described. The periphery of the flange f, above referred to, is fluted and is of the same diameter as the air-inlet tube B. The fluted disk G, above mentioned, 55 has a stem g, operating in suitable webs g' g', is limited in its movement by the stop g³, and is held from rotation by means of the projection g⁴ operating in a vertical keyway. (Shown in dotted lines.) The keyway above 60 mentioned is of such length that the stem is free to be moved up and down in the webs. The disk G is so mounted on the stem that small openings g² are formed between it and the fluted flange f, permitting the passage of 65 air through the same at all times. The tube F is so mounted in the webs b b that it is capable of being reciprocated in the same, so as to increase or decrease the opening between the flange f and the top edge of the air-inlet 70 tube B, whereby the supply of air may be regulated. The tube F is held in its adjusted position by means of friction between it and the webs b b.

The operation of the device is as follows: 75 The wick is lighted through the opening c⁶. Air is drawn in through the perforations c' and also through the openings g², the tube F, together with the flange f, being set to furnish the required amount of air for the 80 flame which is required to heat the mantle to incandescence. As the wick becomes heated the flame thereat becomes smaller and a gas is generated thereby, which rises and burns inside the mantle, thus illuminating the same 85 to incandescence. The air-supply can be further regulated in direction of application to the flame, as well as to quantity, by operating the disk G through the stem g.

In the modification shown in Fig. 2 the air-inlet tube H is closed at the top except for an opening adapted to receive the valve I. This valve I is cylindrical in form, is provided with a dome-shaped top having a central opening therein, and is also provided with vertical 95 slots i in the lower part thereof. This valve slides in the top of the tube H and has a stem i², secured to a web in the bottom thereof.

The operation of this form of our device is similar to that of the former already described. The valve being raised and the openings made by the slots *i* increased in length, 5 more air is admitted to the burner.

Fig. 3 discloses a construction where the air-inlet tube *K* is provided at the top with a perforated reduced portion *k*, extending to a point adjacent to the mantle. Operating 10 within this portion *k* is the valve *L*, which is adapted to fit snugly within the said portion *k* and which has a dome-shaped top provided with an opening *l*² therein, through which air is admitted at all times. A stem *l*¹ is secured to said valve *L* by means of the web *l*³. In this instance the valve *L* is moved upward, 15 thus exposing a larger number of perforations in the portion *k*, and hence admitting more free air to the burner, as is clearly shown in 20 the drawings.

Having described our invention, what we claim, and desire to secure by Letters Patent, is—

1. In an incandescent burner for oil-lamps, 25 the combination with a reservoir having an air-inlet tube, of a chimney-support perforated adjacent to the top of the wick, an inner tube provided with a flange adapted to regulate the free air-supply through said air- 30 inlet tube, a disk adapted to substantially close the opening in said inner tube and means for operating said disk whereby the air-supply passing therethrough may be regulated, substantially as described.
- 35 2. In an incandescent burner for oil-lamps, the combination with a reservoir having an

air-inlet tube communicating with the burner, of a chimney-support perforated adjacent to the top of the wick and provided with an opening whereby access may be had to the said 40 wick, a door for closing said opening, an inner tube provided with a flange adapted to regulate the free air-supply through said air-inlet tube, a disk adapted to substantially close the opening in said air-inlet tube and 45 means for operating said disk whereby the air-supply passing therethrough may be regulated, substantially as described.

3. In an incandescent burner for oil-lamps, the combination with a reservoir having an 50 air-inlet tube communicating with the burner, of webs secured within said air-inlet tube, an inner tube provided with a flange, said inner tube being adapted to operate in said webs and also to regulate the free air-supply through 55 said air-inlet tube, webs secured within said second-mentioned air-inlet tube, a disk having a stem, said disk substantially closing the opening in said inner tube, and said stem being adapted to operate in said webs within 60 said inner tube, whereby the air-supply passing therethrough may be regulated, and means whereby said stem is held from rotation in said webs, substantially as described.

In testimony whereof we affix our signatures in presence of two witnesses.

JOHN MCFARLANE.
EDWARD D. STERNE.
